UNITED STATES PATENT OFFICE.

ELLISON EDWARD VANDERHOEF, OF RUTH, NEVADA, ASSIGNOR TO AMERICAN MAN-
GANESI STEEL COMPANY, OF AUGUSTA, MAINE, A CORPORATION OF MAINE.

BAIL FOR DIPPER-BUCKETS.

1,207,245.

Specification of Letters Patent.

Patented Dec. 5, 1916.

Application filed May 18, 1916. Serial No. 98,289.

To all whom it may concern:

Be it known that I, ELLISON EDWARD VANDERHOEF, a citizen of the United States, and a resident of Ruth, in the county of White Pine and State of Nevada, have made and invented certain new and useful Improvements in Bails for Dipper-Buckets, of which the following is a specification.

My invention relates to a bail such as is used in connection with dipper buckets.

It has been the practice, heretofore, to form the dipper bail and the attaching clevis as separate parts, and to secure the two together by means of rivets, bolts, or other fastening means. The class of service in which these structures are employed and the lack of proper lubrication between the clevis and the clevis pin and pulley block, cause the clevis to loosen upon the bail, and in time to be completely separated and torn therefrom, and the lack of proper lubrication between the clevis and clevis pin often results in excessive wear and injury to the pulley block. I have overcome these difficulties by forming the clevis or attaching member as a part of the dipper bail, and so arranging and designing the members that the lubricant with which the hoisting chain or cable is provided is utilized in maintaining the bearing between the attaching member and attaching member pin in a thoroughly lubricated and proper working condition, the result being that the bail is capable of rendering long and satisfactory service.

A further object is to provide a bail which can be economically manufactured.

Other objects and advantages will appear as the description proceeds, wherein it is to be understood that changes in the precise embodiment of the invention can be made within the scope of what is claimed without departing from the spirit thereof.

The preferred embodiment of my invention is disclosed in the accompanying drawings, wherein:

Figure 1 is a view in front elevation of a dipper bail embodying the characteristic features of my invention, portions of the pulley block to which it is attached being illustrated; Fig. 2 is a vertical-sectional view taken on the line 2-2 of Fig. 1; Fig. 3 is a fragmental view in top plan of the central portion of the dipper bail.

Referring specifically to the several views,

the bail body 5 is formed in the nature of a fabricated structure, and is provided at its center with two spaced flanges 7. These flanges project above the bail body and enlarge and form an integral attaching member 8.

The attaching member 8 comprises a head 9, substantially cylindrical in outline, through which extends an opening or bore 10. The attaching member pin 11, which is carried by spaced attaching arms which project below the pulley block 12, extends through the bore or opening 10 in the cylindrical head and effects a rotatable bearing therewith. The head 9 of the attaching member is connected to the bail body 6 by the flanges 7 and by a web 14, the entire construction being such as to withstand the jars and shocks, severe strains and rough usage to which the bail will be necessarily exposed in service. The spaced attaching arms which project below the dipper block receive therebetween the cylindrical head of the attaching member, which is substantially equal in length to the spacing of the said attaching arms, whereby an efficient joint between the attaching member and pulley block is obtained.

In order that the bearing between the attaching member pin and attaching member may be maintained in a thoroughly lubricated condition, the head is provided at its upper portion with a slot or opening 15, which communicates with the bore 10. The slot 15 is located in close proximity to the hoisting chain or cable 13, which extends around the pulley block, and lies directly beneath the lowermost point thereof. The chain or hoisting cable is always covered or coated with a lubricant, such as a heavy grease, which grease is deposited upon the head of the attaching member as the chain or cable is moved. The location of the slot or opening 15 is such that this lubricant passes through said slot 15 and thoroughly oils and lubricates the bearing between the attaching member pins and attaching member and provides for the free oscillation of the bail with respect to the pulley block.

What I claim is:—

1. A bail comprising a bail body, an attaching member formed integral with, and projecting above, said body, said attaching member including a head with a bore extending therethrough, said head provided

with a slot extending through the top portion thereof and communicating with said bore.

2. The combination of a bail body, an attaching member carried thereby and including a bored head, a pulley block frame, an attaching member pin carried thereby and extending through the opening in said attaching member head, a hoisting member extending around said pulley block, said attaching member head provided with an opening therein located adjacent said hoisting member and communicating with the bearing between said attaching member head and said pin.

3. The combination of a dipper bail, an attaching member rigidly carried thereby, said attaching member provided with an opening extending therethrough, a slot extending through the top of said attaching member and communicating with said opening, and a pulley block pivotally secured to said attaching member and located in close

proximity to the slot in the attaching member and adapted to supply a lubricant 25 thereto.

4. In combination, a pulley block with spaced attaching arms projecting therebelow, a dipper bail with an upwardly projecting attaching member formed integral therewith, said attaching member including a cylindrical head substantially equal in length to the spacing of the attaching arms of said pulley block and fitting therebetween, said attaching member and attaching arms of the 30 pulley blocks provided with aligned cylindrical openings, and a pin extending therethrough for the pivotal securing of the two.

Signed at Ely, in the county of White 40 Pine, and State of Nevada, this tenth day of May, A. D. 1916.

ELLISON EDWARD VANDERHOEF.
